UNITED STATES PATENT OFFICE.

CONOVER T. SILVER, OF NEW YORK, N. Y.

DESIGN FOR AN AUTOMOBILE.

54,134.

Specification for Design.

Patented Nov. 4, 1919.

Application filed May 2, 1919. Serial No. 294,333. Term of patent 14 years.

To all whom it may concern:

Be it known that I, CONOVER T. SILVER, a citizen of the United States, residing at New York city, borough of Manhattan, in the county of New York and State of New York, have invented a new, original, and ornamental Design for an Automobile, of which the following is a specification, reference being had to the accompanying drawing, forming part thereof.

Figure 1 is a side elevation of the automobile;

Fig. 2 is a plan view;

Fig. 3 is a front view; and

Fig. 4 is a rear view.

I claim:

The ornamental design for an automobile, as shown.

CONOVER T. SILVER.
